Primary Examiner — Calvin E Vansant*Assistant Examiner* — Sydney M Evans(74) *Attorney, Agent, or Firm* — Gwendoline Bruneau; Lavery, de Billy, L.L.P.(57) **CLAIM**

The ornamental design for a hoe as shown and described.

DESCRIPTION

FIG. 1 is a perspective view of the hoe showing our new design;

FIG. 2 is a front view of the hoe;

FIG. 3 is a rear view of the hoe;

FIG. 4 a first side view of the hoe;

FIG. 5 is a second side view of the hoe;

FIG. 6 is a top view of the hoe; and,

FIG. 7 is a bottom view of the hoe.

The dashed broken lines showing environmental structure and the dash-dot lines indicating a symbolic break in length form no part of the claimed design.

1 Claim, 7 Drawing Sheets(56)
